(57) **CLAIM**

The ornamental design for a hub of vehicle wheel, as shown and described.

DESCRIPTION

1. Hub of vehicle wheel

1.1 is a left side perspective view of a hub of vehicle wheel embodying our new design;

1.2 is a front elevation view thereof;

1.3 is a left side elevation view thereof;

1.4 is a right side elevation view thereof; and

1.5 is a right side perspective view thereof.

The broken lines in the reproductions illustrate portions of the hub of vehicle wheel that form no part of the claimed design.
